UNITED STATES PATENT OFFICE.

JAMES F. CAVANAGH, OF PHILADELPHIA, PENNSYLVANIA.

TROUSERS-LEG HOLDER.

1,017,511.

Specification of Letters Patent.

Patented Feb. 13, 1912.

Application filed August 2, 1911. Serial No. 641,893.

To all whom it may concern:

Be it known that I, JAMES F. CAVANAGH, a citizen of the United States, residing at Philadelphia, in the county of Philadelphia and State of Pennsylvania, have invented 5 certain new and useful Improvements in Trouser-Leg Holders, of which the following is a specification, reference being had to the accompanying drawings.

10 This invention is an improved device for use by bow-legged men to keep the trousers legs from bending in on the inner sides and to hence conceal or modify the deformity, the invention consisting in the construction, 15 combination and arrangement of devices hereinafter described and claimed.

The object of my invention is to provide an improved device of this character which may be readily and expeditiously attached 20 to the leg, which does not incommode the user and which is extremely cheap and simple.

In the accompanying drawings: Figure 1 is a plan of a trousers leg holding device 25 constructed in accordance with my invention, showing the same attached to a garter, the cross sectional shape of the trousers leg in which the device is used being indicated in dotted lines; Fig. 2 is partly an elevation 30 of the same and partly a section on the line *a—a* of Fig. 1; Fig. 3 is a detail perspective view of the leg holding bar; Fig. 4 is a detail perspective view of one of the clip plates employed for connecting the leg holding bar 35 to the band formed by the garter; and Fig. 5 is a sectional view on the plane indicated by the line *b—b* of Fig. 2.

In accordance with my invention I provide a bar 1 which is designed to be worn 40 on the leg of the user, on the inner side thereof, and to bear against the inner side of the trousers leg so as to keep the trousers leg from bowing in and to thereby conceal the deformity of the leg or at least greatly 45 modify and reduce the effect of the appearance of the same. This bar is preferably elastic so that it will conform to the shape of the trousers leg cross sectionally, and, in practice, I make this bar of rubber so that 50 while it is sufficiently strong to hold the trousers leg in shape it will flex to some extent and conform to the cross sectional shape of the trousers leg and its use will not be noticed. This supporting or holding bar 55 is carried by a suitable band or other device which engages the leg of the user. This

band 2 is here shown as a garter of usual form.

Within the scope of my invention any suitable means may be employed to connect the holding bar to the attaching device or band. I have preferably employed and here show a pair of clip plates 3 for this purpose. Each of these clip plates is provided with a pair of openings 4 through which the 60 garter or band is passed, as shown, and each plate is also provided near its outer end with an opening 5, the outer end of the plate being doubled and bent to form a securing lip 6. The bar 1 is provided near its ends with 65 inturned reversely curved attaching members 7 which are preferably formed integral with the bar, by slitting the ends of the bar on parallel lines 8 as shown in detail in Fig. 3, so that not only are the attaching devices 7 formed at the ends of the bar but the latter is also provided with flexible fingers or arms 9, which bear against the inner side 70 of the trousers leg and flex readily so as to conform to the cross sectional shape of the 75 trousers leg and prevent the use of the bar from being noticed. The inturned ends of the attaching devices 7 are passed between the clip plates 3 and the band 2, out through the openings 5 of the said clip plates and are 80 doubled and bent and engaged by the lip 6 at the outer ends of the clip plates and hence the bar is connected to the clip plates and is spaced from the band or attaching device 85 90 by the attaching arms 7. These arms, being of rubber, are flexible and form yielding or cushioning connections between the bars and the attaching device or band and readily yield to the motions of the user and co-act with the bar 1 in preventing the inner 95 side of the trousers leg from bending in. Hence the bar, being spaced from the inner side of the leg engaging band, adjusts itself by the action of the elastic attaching arms 7 and keeps the inner side of the trousers leg 100 straight, thereby concealing the misshapeness of the leg of the user.

Having thus described my invention I claim:

1. A trousers leg holding device of the 105 class described embodying an elastic bar, a leg engaging device, and means for connecting the said bar and the leg engaging device, said connecting means being spaced from the ends of the bar, spacing the bar from the leg 110 engaging device and holding the bar in a substantially horizontal position.

2. A trousers leg holding device of the class described embodying an elastic bar provided with elastic fingers at its ends, a leg engaging device and means connecting the said bar and the leg engaging device, said connecting means being spaced from the ends of the bar, spacing the bar from the leg engaging device and holding the bar in a substantially horizontal position.
- 10 3. A trousers leg holding device of the class described embodying an elastic bar, a leg engaging device and elastic means connecting the said bar and the leg engaging device, said elastic connecting means being spaced from the ends of the bar, spacing the bar from the leg engaging device and hold-
- 15

ing the bar in a substantially horizontal position.

4. A device of the class described comprising a band to engage the leg of the user, clip plates connected to and adjustable on the band, an elastic bar to bear against the inner side of a trousers leg, and elastic attaching devices between the clip plates and the bar to space the latter from the clip plates and 25 yieldingly support said bar.

In testimony whereof I hereunto affix my signature in the presence of two witnesses.

JAMES F. CAVANAGH.
